ADVERTISING CALENDAR DEVICE

Application filed April 16, 1930. Serial No. 444,708.

Our invention primarily, comprises a calendar consisting of a base and a series of independent disks rotatably mounted and independently rotatable by manual operation.

5 One object of the device is to provide a substantially constructed calendar perpetual in form, and wherein the days, months and years are visibly brought to view instantaneously and without the necessity of lifting, 10 turning, underslipping and removing of leaves, common to calendar in general use.

Another object of the device is to provide 15 a calendar incorporating a clock, and co-incidentally enable the viewing public to observe the time, day, date, month and year at a glance, the daily changes being readily made and requiring but a few seconds of time.

Still a further object of the device is the 20 provision of a means indicating special events, and comprising a block of movable cards on which are printed special announcements, the legal holidays, the birthday, date of death and picture of past and present Presidents, and historic events, for example. Each topic is listed on a separate card. 25 As the day arrives corresponding with a certain topic, the card bearing same is brought forward and exposed to view by placing it in the front of the outer cards.

30 The invention lends itself further in its unique features which afford wonderful possibilities for advertising purposes, the base providing a surface area allowing considerable latitude, and as the device is perpetual in scope, that is, may be used from year to year, 35 it presents a marked advance in the calendar art.

The invention will be best understood from 40 a consideration of the following detailed description of the accompanying drawings forming a part thereof, and wherein Figure 1 is a front view of our improved advertising calendar device; Figure 2 being a section-view thereof taken directly through 45 the center; Figure 3 is a front view of our device indicating a similar construction, indicating, however, a clock centrally positioned therewith, while Figure 4 is a sectional view thereof taken directly through 50 the center as in Figure 2.

Similar numerals of reference indicate like parts throughout the several views, the numeral 1 thus indicating a base or backing for the device on which is suitably mounted a block 2 of removably affixed cards as afore- 55 said, the numeral 3 indicating one form of mounting means forming stud members comprising bolts 3 and nuts 4.

Attached to said base 1 by means of a trunnion of either solid or hollow formation 60 so as to comprise a spindle shaft 15 secured to the base by means of the nut 16, are a series of dial members, the drawings indicating four of them, these are mounted to the base in the following order:—that designated 19 first, 65 said dial having imprinted around its circumferential face at the extreme outer edge thereof, the names of the twelve calendar months of the year. Dial 10 is attached next in order, the latter having imprinted thereon in a similar position, the numerals 16 to 31 inclusive, dial 9 following, the latter duplicating dial 10 in this respect excepting that the numerals thereon run from 1 to 15 inclusive, the numerals in both instances being 70 designated on the drawing by the numeral 11, the two dials comprising the calendar date dials, each number representing one of the days of a month, dial 9 having a cut away portion 12 so that the numerals imprinted on 75 dial 10 can be brought to view. The device is not limited to two date dials, since the larger the device, the larger these numerals must be, hence, a plurality of such dials may be required to adequately take care of the 80 numbering caused by the increased size of same, and it is equally apparent, that for a small device, but one dial whereon the entire 31 numbers can be placed, would suffice. Dial 5 is the last dial secured to the shaft, and is 85 actually the only one entirely brought to view, a cut away portion 6 therein corresponding to the cut away portion 12 in dial 9 forming a means for bringing the numerals on either of aforesaid dials to view in connection 90 with the portion 12.

It will be understood from the drawings that dials 5, 9 and 10 are of equal size, while dial 19 has a greater diameter to allow for the space required for imprinting the names 100

of the calendar months which are always exposed to view. Dial 5, on the other hand differs from these in that it is stationary, the head of the shaft being arranged to grip the same. Imprinted on dial 5 are indicator members 7 and 8, also a series of lines which serve merely to align with the month designations imprinted on dial 19.

Independently pivoted to the base 1 is 10 also a smaller dial 13 arranged with tabs to indicate the days of the week, said tabs having the week day designated as in 14, the dial being secured to the base by any suitable means, bolt 17 and nut 18 being one means.

15 In the modification shown in Figures 3 and 4, a clock is incorporated in the device, the clock 20 being secured to the base by a flanged ring 21.

20 It will be noted that the dials must be bored to permit the face of the clock to set flush or nearly so with the face of the calendar dial 5.

It is obvious that the device can be made in any desired size, the greater the size, the more 25 numerous the date dials as aforesaid.

30 Simplicity is the keynote of its construction. It is apparent that the device is readily produced from materials obtainable at low cost in the open market, such as card board, card cloth, celluloid, lumber, veneering and sheet metal, a suitable card board serving the purpose quite well.

35 The design of the base member requires no special adaptation, but may as readily be oblong as square, oval, circular or other formation, it may be trimmed, cut, embellished and colored to suit the taste and fancy of the maker, or as required for any special job.

40 We are aware that some changes may be made in the general arrangement and combination of the device, as well as in the details of the construction of the same, without departing from the scope of the present invention 45 as set forth herein, and as defined in the claim appended hereto. It is also obvious that the device is as readily serviceable without the clock in combination as a perpetual calendar as it is therewith, and that therefore a 50 clock may or may not be incorporated, it being expedient to produce the same made up in both styles, leaving it up to the purchasing public as to what style or type might suit them best. Hence, we do not limit our invention 55 exclusively to the exact arrangement and construction indicated and described, but what we do claim is:—

60 In a calendar device comprising a fixed base portion supporting in the order named, a 65 movably positioned dial member having imprinted thereon the names of the twelve calendar months of the year, a movably positioned dial member having imprinted thereon certain of the dates of the days of the month, a further movably positioned dial member

having a cut-a-way portion and imprinted thereon certain other of the dates of the days of the month, a fixed dial member having imprinted thereon a series of lines and indicator members, and having a cut-a-way portion for 70 exposing a month date, and an independent dial member rotatably affixed to the base, and having a body portion positioned beneath the first-mentioned dial members and tabs having imprinted thereon the days of the week, which 75 may be successively exposed beyond said first mentioned dial members by the rotation of the independent dial member.
